UNITED STATES PATENT OFFICE.

JONATHAN F. ELLSWORTH, OF HYANNIS, NEBRASKA.

SNAP-HOOK.

SPECIFICATION forming part of Letters Patent No. 744,860, dated November 24, 1903.

Application filed March 18, 1902. Renewed May 14, 1903. Serial No. 157,139. (No model.)

To all whom it may concern:

Be it known that I, JONATHAN F. ELLSWORTH, a citizen of the United States, residing at Hyannis, in the county of Grant and State of Nebraska, have invented certain new and useful Improvements in Snap-Hooks; and I do declare the following to be a full, clear, and exact description of the invention, such as will enable others skilled in the art to which it appertains to make and use the same.

The invention relates to snap-hooks and is designed as an improvement on Letters Patent No. 676,981, granted June 25, 1901.

In the patent above referred to I have discovered that the loops to which the cross-bar is connected greatly weakens the side pieces, and to overcome this objection I have provided the side bars with reinforcing-sleeves, which bridge the opening between the sides 20 of the loops, and thus materially strengthens the side pieces.

The invention consists of a snap-hook comprising a split ring and a halter-receiving part connected by side wires, said ring opening upon compression of the hook, and a device situated intermediate the side wires to cause the lateral separation of the parts of the opened ring by compression of the hook, said device comprising a transverse loop in 30 each wire, connected to its fellow by a bar, and sleeves for closing or bridging the space formed between the sides of the loops, and thus materially strengthening the side pieces and relieving them of strain at those points 35 at which the loops are formed.

In the accompanying drawings, Figure 1 is a perspective view of my improved snap-hook. Fig. 2 is a transverse section looking toward the split ring, showing in full lines the members of the split ring closed and in dotted lines showing them open. Fig. 3 is a transverse sectional view through one of the loops looking down upon the sleeve; and Fig. 4 is a view of one of the side pieces of the snap-hook, illustrating the loop before the sleeve has been applied.

Referring to the drawings, 1 denotes a so-called "snap-hook" formed of a single piece of wire bent to produce a strap-receiving part

2 and having its ends bent and overlapped, 50 as shown, to form a split open ring 3 for the reception of a closed strap-ring or strap. Preferably the ring 3 and the part 2 are made of unequal size, as shown, and connected by side wires 7 of usual form, except that they 55 are provided with short open loops or bends 8, extending oppositely from the side wires, as represented. The outer portions of said bends are joined by a transverse obliquely-disposed bar 9, the main purpose of which is 60 to cause the side wires 7 to move in planes uniformly situated with respect to each other in order to move the wire ends 5 obliquely apart, as indicated in Fig. 2 in full and broken lines. 65

In practice it has been found that the side wires or pieces 7 are materially weakened by forming the loops or bends 8 therein, and to overcome this objection I provide a split sleeve 10, which bridges the space formed by 70 the side pieces 11 of the loops and surrounds the pieces 7 immediately contiguous to the side pieces of said loops and extends some little distance along the side pieces 7 in the opposite direction from said loops. The present invention lies in this feature and materially increases the life of the snap-hook. 75

Having thus described my invention, what I claim, and desire to secure by Letters Patent, is— 80

A snap-hook comprising a split ring, and a halter-receiving part connected by side wires, said ring opening upon compression of the hook, and a device situated intermediate the side wires to cause the lateral separation of the parts of the opened ring by compression of the hook, said device comprising a transverse loop in each wire connected to its fellow by a bar, and sleeves for closing or bridging the space formed between the sides of the loops, substantially as set forth. 90

In testimony whereof I have hereunto set my hand in presence of two subscribing witnesses.

JONATHAN F. ELLSWORTH.
